UNITED STATES PATENT OFFICE

FOREST H. THORPE, OF COLUMBUS, OHIO, ASSIGNOR TO THE COLUMBUS SUCKER ROD COMPANY, OF COLUMBUS, OHIO, A CORPORATION OF OHIO

AUXILIARY LIFT

Application filed September 13, 1929. Serial No. 392,323.

This invention relates to auxiliary lifts for use in connection with oil wells. It particularly relates to means for admitting gas or air pressure from the exterior of the oil pipe 5 to the interior thereof, to aid in the lifting of the oil from the well up through the pipe.

It is particularly the object of this invention to provide one or more of these devices adapted to aid in hoisting the oil by means 10 of pressure in the well through one or more stages of the depth of the well.

For the purpose of illustration there is shown in the accompanying drawings a preferred embodiment of this invention, in which 15 one device is used.

Referring to the drawings:

Figure 1 is a vertical section through the well casing, the oil pipe and one of the devices, showing the valves used in connection 20 therewith.

Figure 2 is a bottom plan view of the device with the oil pipe and casing in section.

The well casing is indicated by the numeral 1 and may be of any suitable size or length. 25 The oil pipe is indicated by the numeral 2 and fits within the casing with some considerable space between the walls thereof, which is occupied by gas or air under pressure.

In order to confine the pressure within the 30 casing and around the oil pipe the upper part of the casing may be closed, and in case the pressure of the natural accumulation of gas within the casing is not sufficient to force the oil up through the oil pipe, air may be 35 pumped into the casing around the oil pipe, or air pressure alone may be used.

It has been found by actual observation 40 that the pressure of the gas within the casing is several times greater near the top than at the bottom of the well. For instance, the pressure may be as much as one hundred pounds at the bottom of the well, whereas near the top of the well the pressure may be eight hundred pounds, and it is for the purpose of using this additional pressure in elevating the oil that this apparatus is devised and formed.

The adjacent ends of the sections of the oil pipe are screw threaded, as indicated by 50 the numeral 3. The body of the device which

may be used for uniting the sections of pipe is indicated by the numeral 4, and is screw threaded at each end of a hole 5. The screw threads are indicated by the numeral 6. The hole 5 serves as a passageway for the oil 55 through the device and is in line with the sections of the pipe.

There is also arranged in the body, as indicated in the figures, one or more chambers 7. These chambers are shown in the present 60 drawings to be four in number but any suitable number may be used, and as shown in the drawings the upper end of each chamber is closed, whereas the lower one is open and is screw threaded as indicated by the number 65 8.

Within the screw threaded end of each chamber is a plug 9 which has a passageway 10 therethrough. The upper part of this passageway leads into a pressure cavity 11. 70 The lower part of the plug surrounding the passageway has a depression 12 which aids in directing the gas through the passageway up into the chamber. There is also provided in the plug a slot 13 to receive a screw driver 75 for the purpose of removing or placing the plug within the chamber.

The edge of the plug surrounding the pressure cavity is beveled to form a valve seat 14. Resting upon this valve seat is a ball 80 valve 15 which has resting thereon a weight 16. This weight may be of any size, dependent upon the amount of pressure needed at the particular location for the opening of the valve and the admission of gas into the oil 85 pipe. The weight might be dispensed with by making the ball valve of sufficient weight.

Leading from the chamber 7 and adjacent the upper end of the plug 9 is a duct 17 leading into the oil pipe. When a sufficient 90 amount of gas pressure has accumulated within the casing 1 the ball 15 is raised to permit the passage of gas from the casing outside of the oil pipe through the chambers, ducts 17, into the oil pipe. It is noticed that 95 these ducts 17 lead into the oil pipe in substantially the same direction in which the oil therein is flowing so that as the air or gas enters into the oil pipe it impinges upon the outer surface of the oil and tends to force it 100

upwardly in the same direction in which the gas is moving and in the same direction in which the oil is flowing.

There may be any number of these devices located at various and suitable points along the length of the oil pipe for the purpose of using the pressure in the casing, while at different points each device admits gas or air under pressure, to aid in elevating the oil.

10 It is to be understood that I may use a single valve and may so construct the valve as to dispense with the weight for closing the same. The oil pipe may also be so constructed that the valve or valves will be located therein instead of in a separate unit.

15 I desire to comprehend within my invention such modifications as may be clearly embraced within my claims and the scope of my invention.

20 Having thus fully described my invention, what I claim is new and desire to secure by Letters Patent, is:

25 1. In an auxiliary lift, a union member having a longitudinal passage therein, a plurality of longitudinal chambers in said member with a diagonal duct for each chamber leading into the passage, a plug in one end of each chamber, said plug having a restricted passageway terminating in a pressure cavity and a valve seat, a ball valve adapted to rest in said seat and close the passageway, and a weight resting loosely upon each ball.

30 2. In an auxiliary lift, a union member having a longitudinal passage therein, a plurality of longitudinal chambers in said member with a diagonal duct for each chamber leading into the passage, a plug in each chamber, said plug having a passageway including a fluid-directing depression, a pressure cavity and a valve seat, a ball valve adapted to rest in said seat and close the passageway, and a weight resting loosely upon the ball.

35 In testimony whereof, I affix my signature.

40 FOREST H. THORPE.
